Patented Sept. 23, 1975

236,863

SOAP DISH BRACKET

Raymond U. H. Tegner, Lodi, Wis., assignor to
Amerock Corporation, Rockford, Ill.

Original design application Jan. 4, 1974, Ser. No.
430,938. Divided and this application Sept. 3, 1974,
Ser. No. 502,884

Term of patent 14 years

Int. Cl. D6—04

U.S. Cl. D6—90

FIG. 2.

FIG. 3.

FIG. 4.

FIG. 5.

FIG. 1 is a front view of a soap dish bracket incorporating my new design.

FIG. 2 is a side view as seen from the right in FIG. 1.

FIG. 3 is a top view of the bracket.

FIG. 4 is a bottom view of the bracket.

FIG. 5 is a sectional view taken along the line 5—5 in FIG. 1.

This application is a division of my co-pending application Ser. No. 430,938, filed Jan. 4, 1974.

I claim:

The ornamental design for a soap dish bracket, as shown.
